Primary Examiner — Michael C Stout

Assistant Examiner — Fitzgerald L Butac

(74) Attorney, Agent, or Firm — Harness, Dickey & Pierce, P.L.C.

(57) **CLAIM**

The ornamental design for a transmission intermediate plate, as shown and described.

DESCRIPTION

FIG. 1 is a front perspective view of the transmission intermediate plate;

FIG. 2 is a front planar view thereof;

FIG. 3 is a left side view thereof;

FIG. 4 is a top view thereof;

FIG. 5 is a right side view thereof;

FIG. 6 is a bottom view thereof; and,

FIG. 7 is a rear view thereof.

1 Claim, 5 Drawing Sheets
